(57) **CLAIM**

We claim the ornamental design for a display screen or portion thereof with an animated graphical user interface, as shown and described.

DESCRIPTION

FIG. 1 is a front view of a display screen or portion thereof with a first embodiment of an animated graphical user interface showing a first image in the sequence of our new design;

FIG. 2 is a second image of the first embodiment thereof;

FIG. 3 is a third image of the first embodiment thereof;

FIG. 4 is a fourth image of the first embodiment thereof;

FIG. 5 is a fifth image of the first embodiment thereof;

FIG. 6 is a front view of a display screen or portion thereof with a second embodiment of an animated graphical user interface showing a first image in the sequence of our new design;

FIG. 7 is a second image of the second embodiment thereof;

FIG. 8 is a third image of the second embodiment thereof;

FIG. 9 is a fourth image of the second embodiment thereof; and,

FIG. 10 is a fifth image of the second embodiment thereof. The two outermost broken lines from the graphical user interface illustrate the display screen. The remaining broken lines illustrate portions of the graphical user interface that form no part of the claimed design. None of the broken lines form part of the claimed design.

The appearance of the animated images sequentially transitions between the images shown in FIGS. 1-5 for the first embodiment and FIGS. 6-10 for the second embodiment. The process or period in which one image transitions to another forms no part of the claimed design.

1 Claim, 10 Drawing Sheets
